PUMP

Albert F. Ruthven, Lincoln, Nebr., assignor to
 Ruthven Side-Pocket Dam Corporation, Lincoln, Nebr., a corporation of Colorado

Application March 26, 1943, Serial No. 480,597

2 Claims. (Cl. 103—204)

This invention relates to improvement in pumps and especially to pumps having hollow cylindrical plungers reciprocable within pump barrels and usually operated at high speeds.

Objects of the invention are to provide, in a pump of the class described, (a) improved means for getting lubrication to the adjacent surfaces of the barrel and plunger; (b) improved means for eliminating or substantially reducing injury to the adjacent surfaces of the barrel and plunger resulting from sand or other solids settled or accumulated from the liquid being pumped, and (c) an improved structure in the wall of the plunger which shall, coincidentally, accomplish, or contribute to the accomplishment of, both of these objects.

With these, and other objects in view, all of which shall more fully hereinafter appear, the invention comprises certain novel constructions, combinations and arrangements of parts as hereinafter described and claimed and as illustrated, in preferred embodiment, in the accompanying drawing in which

Fig. 1 is a longitudinal section of a fragment of a pump barrel with a plunger therein, the plunger being shown partly in elevation and partly in section, the sectioned portion disclosing a check valve carried by the plunger at its lower end.

Fig. 2 is a bottom view of the structure shown at Fig. 1, the barrel, however, being shown in full lines.

Fig. 3 is a sectional view on line 3—3 of Fig. 1.

Fig. 4 is an enlarged and somewhat exaggerated view of the bucket portion of Fig. 3.

A plunger, construed according to this invention, may be installed in a cylindrical barrel of any pump, and, accordingly, I have disclosed in the drawing only a portion of a conventional barrel 10 having reciprocably positioned therein a hollow cylindrical plunger 11, only sufficient clearance being provided between the barrel, and the plunger to avoid friction, such clearance being preferably between $\frac{1}{1000}$ and $\frac{1}{1000}$ of an inch.

Any suitable check valve is provided at the lower end of the plunger, the valve assembly here illustrated being convenient for this purpose and comprising a base 12 having a central bore 13 at the top of which bore is a valve seat 14 for a ball valve 15. The base has a threaded engagement with the lower end of the plunger as at 16 whereby, when assembled, the plunger and base become a unit. The base is provided with an upstanding cage or runway 17 for ball 15 and the usual sucker rod 18 is attached to the top of the cage whereby

the plunger and valve assembly are reciprocated as a unit by the sucker rod.

It will be understood that as the plunger is lowered, liquid, from the lower part of the barrel, enters the interior of the plunger through the valve, and that as the plunger is raised the valve closes and the liquid within the plunger is lifted in the usual manner.

The clearance between the barrel and plunger 10 permits the entrance of a film of liquid between the walls of the barrel and plunger which film acts as a lubricant.

Under ordinary operative conditions the fluid being pumped carries some sand or similar solids hereinafter included in the term "sand." During continuous operation of such a pump, at high speeds, the sand is carried by the rising column of liquid and does not settle in or around the plunger nor does any appreciable amount find its way into the clearance between the walls of the barrel and plunger. When, however, the pump is not operating, sand, from the column of liquid above the plunger, settles onto the top edge to the plunger and against the wall of the barrel 25 and bridges the top of the clearance space between the walls of the plunger and barrel. When the pump is again started, this accumulated sand tends to work down into the clearance space and score the walls of the barrel and plunger. This 30 is especially true when the plunger has been stopped at the bottom of its stroke so that, upon again starting the pump, the first movement of the plunger is upward. Also if the plunger has come to rest in a slightly off-center position so 35 that the top of the plunger lies against the barrel wall on one side and correspondingly enlarges the clearance space on the opposite side, the danger of sand working down between the walls is, obviously, increased.

40 I am aware that efforts have heretofore been made to collect and remove the sand which finds its way from above into the clearance space and that for that purpose annular grooves have been formed in the external wall of the plunger, thereby 45 providing a place for the sand to settle, out of the area of clearance between the walls of the barrel and plunger. Sand collected in such grooves settles and packs and requires periodical cleaning and also tends to work out of the groove 50 and downwardly between the barrel and plunger walls. To remedy this trouble and, coincidentally to provide more efficient lubrication between the barrel and plunger walls, as is required for high speed pumps, are the principal purposes of the 55 present invention and these purposes are accom-

plished by the improvement now more specifically described.

Generally, the invention consists in grooving and perforating the wall of the plunger, the groove being provided to catch any sand which finds its way down around the outside of the plunger and also to furnish a channel for circulation of fluid, and in perforating the wall of the plunger at the bottom of the groove, thereby forming communication between the groove and the interior of the plunger whereby fluid may circulate in the groove and, in either direction, between the groove and the plunger interior.

Two such grooves are illustrated and are indicated by 19 and 19a respectively. Two sets of conduits are illustrated in each of the grooves. The sets are designated as 20 and 21 respectively. Two grooves are not essential but are preferable. More than two may be used and, in case of long plungers, more would be desirable. It will be noted that the conduits or orifices 20 are radial while those designated as 21 are angled, relative to the radius of the plunger. The use of both radial and angled conduits is preferable but the angled orifices are of greater importance as will clearly appear hereinafter. These conduits 20 and 21 are all horizontal, that is to say, their axes lie in a plane perpendicular to the axis of the plunger as clearly shown at Fig. 3. This horizontal positioning of the conduits is important in order to reduce to a minimum the entrance into the conduits of sand, moving up or down in the center of the plunger. Such conduits opening either upwardly or downwardly into the plunger chamber would tend to catch sand moving up or down in the chamber and conduct it into the annular groove.

One purpose of the groove is to catch sand which has worked into the clearance at the top and to prevent the sand injuring the wall. For this purpose it is clearly desirable to place the groove near the top of the plunger so as to catch the sand, and take it out of the area between the walls, as soon as possible. The groove, however, has another purpose, namely, to receive liquid which will come through orifices 20 and 21 from the inside of the plunger, while the plunger is being raised, and enable such liquid to circulate in the groove and contact and lubricate the wall of the barrel and seep down in the clearance for lubricating the walls of the plunger and barrel. For accomplishing this lubricating function the most efficient location of the groove is at or near the midsection of the plunger. This is especially true in the case of long plungers, because the longer the plunger the greater is the danger of lack of lubrication at the central part of the plunger if the lubricating fluid can enter the clearance only at the top and bottom of the plunger.

It, therefore, appears that for the sand catching purpose alone, the groove should be near the top of the plunger while for the lubrication purpose alone, the groove should be near or a little above the middle of the plunger.

With short plungers both purposes can be accomplished with substantial efficiency by providing one groove somewhat above the middle of the plunger.

In the case of long plungers it is preferable to provide one groove near the top, and another near the middle, of the plunger. In such case the upper groove will collect most of the sand and will contribute some needed lubrication, while the lower groove will collect any sand which

may have escaped the upper groove and will furnish lubrication to the midsection of the plunger and adjacent barrel wall.

The arrangement of the orifices 20 and 21 relative to the groove is of great importance. When the plunger is being lifted the fluid will flow from the interior of the plunger outwardly into the groove, for lubrication as above described. This outflowing liquid also serves another purpose, namely, agitation of the liquid in the groove whereby to prevent the settling and packing therein of the collected sand. For this reason the orifices 20 and 21 are positioned in the lower portion of the groove bottom, that is to say, near the lower side of the groove on which lower side the sand would normally collect and pack. By such low positioning of the orifices the liquid is caused to be ejected therefrom directly into the area in which the sand would normally settle and pack and such ejection tends to prevent such settling and packing.

In this connection, the angular arrangement of the orifices 21 is most important. By reason of such angularity the liquid passing through the orifices 21 emerges therefrom into the groove in a direction which causes a circulatory movement of the liquid in the groove, thus effectively preventing settling and packing of the sand. While the angularity of the conduits 21 is of primary importance, it is also important that some of the conduits, as indicated at 20, be radial because such radial conduits will more effectively collect, from the circulating stream in the groove, the sand particles and lead them out into the main stream in the plunger chamber and thence out of the pump.

When the plunger is forced down into the liquid in the lower part of the barrel such liquid is forced into the plunger not only through the valve but also between the lower portion of the walls of the plunger and barrel and thence into the groove and through the orifices 20 and 21. During this movement the sand-carrying liquid in the groove is forced through the orifices 20 and 21 and into the rising column of liquid and thence out of the pump.

Thus, while each upward stroke of the plunger tends to gather into the groove any sand which has worked down between the walls, the liquid flowing out through the orifices, maintains a circulation and agitation in the groove and keeps the sand in suspension and the succeeding downward stroke of the plunger forces the sand laden liquid from the groove back through the orifices into the water column within the plunger and by this action, repeated with each cycle of movement of the plunger, the present invention, promptly upon resumption of operation of the pump, eliminates any sand which may have accumulated at the top of the plunger during the preceding inoperative period.

While I have illustrated and described certain details of structure in and associated with the illustrated embodiment of my invention, the invention is not, and I am not to be, limited to such details.

I claim:

1. In a pump including a barrel and a hollow cylindrical plunger reciprocable in the barrel, the combination of an annular groove in the outer wall of the plunger and conduits in the plunger wall opening into the groove and into the interior of the plunger, said conduits lying in a plane perpendicular to the axis of the plunger, some of said conduits being radial of the plunger and

others being angular, relative to the radii of the plunger.

2. In a pump including a barrel and a hollow cylindrical plunger reciprocable in the barrel, the combination of an annular groove in the outer wall of the plunger, said groove having a horizontal lower side, and conduits leading from the

interior of the plunger into said groove adjacent said lower side, said conduits lying in a plane perpendicular to the axis of the plunger and some of said conduits being radial of the plunger and others being angular, relative to the radii of the plunger.

ALBERT F. RUTHVEN.
